UNITED STATES PATENT OFFICE.

ANDREW M. COYLE, OF NEW YORK, N. Y.

SELF-ROTATING PROJECTILE.

1,201,263.

Specification of Letters Patent. Patented Oct. 17, 1916.

Application filed October 11, 1915. Serial No. 55,185.

To all whom it may concern:

Be it known that I, ANDREW M. COYLE, a citizen of the United States, and a resident of New York, county and State of New York, have invented certain new and useful Improvements in Self-Rotating Projectiles, of which the following is a specification, reference being had to the accompanying drawings, forming a part thereof.

10 My invention relates to projectiles and it has special reference to such as are adapted to be rotated without the necessity of rifling the gun.

One object of my invention is to provide 15 a projectile that shall be adapted to be discharged from a smooth bore gun and which shall embody means for producing a rapid rotation of the projectile about its longitudinal axis, such means being active only 20 while the projectile is traversing the length of the gun barrel.

Another object is to provide a projectile 25 that shall be adapted to pass through the air with the least possible resistance, its rear end being specially tapered to avoid producing a partial vacuum in its wake.

Another object is to provide a projectile 30 having means for producing its rotation, comprising a particularly advantageous arrangement of tangential pockets containing quick-burning powder held in place by simple and desirable caps and opening into an annular space formed by a reduced section of the projectile, whereby the powder 35 may be discharged and the resulting forces exerted while the projectile is in the gun, against the powerful reaction of the compressed gases produced by the main charge of the gun.

40 I am aware that a rotative movement of a rocket or the like has hitherto been produced by a tangential discharge of explosives while the rocket is traveling through the air at a rapid rate, but such an arrangement would 45 be entirely impracticable for rotating a projectile while it is traveling through the air after it has been discharged from the muzzle of the gun, because it would be impossible to produce a plurality of absolutely balanced tangential forces which would have no influence upon the projectile itself, except to produce rotation. Obviously, if any other action were exerted upon the projectile, its course would be materially altered and the accuracy of the shot entirely destroyed.

Furthermore, the reaction of the atmosphere is small and the effect of charges of permissible size slight.

According to my present invention, I provide a projectile having a plurality of 60 charges of quick-acting explosives which are adapted to be simultaneously fired and tangentially discharged to produce a rapid rotation of the projectile in the gun, the gun being relied upon for imparting the correct 65 direction to the shot so that the projectile is discharged with perfect accuracy without being dependent upon the nicety with which the tangential forces are balanced. The tangential discharges may, and probably will, 70 be somewhat unbalanced but the course of the projectile is obviously held true by the gun and since, in accordance with my invention, the tangential discharge is completely fired, while the projectile is still in the gun 75 and against the reaction of highly compressed gases the objective result is secured, viz., the projectile is rotated at a high speed as it leaves the muzzle of the gun although the gun is smooth bore.

Another advantage of my arrangement arises from the fact that the tangential discharges are so placed relative to the length 80 of the projectile as to assist the main firing charge of the gun.

Other objects and advantages of my invention will be set forth hereinafter, and in order that my invention may be thoroughly understood I will now proceed to describe the same in the following specification and then point out the novel features 90 thereof in appended claims.

Referring to the drawings: Figure 1 is a longitudinal elevation of a projectile embodying my invention, mounted in a gun, a portion of which is shown in section. Fig. 2 is a transverse sectional elevation, taken on the line 2—2 of Fig. 1. Fig. 3 shows a single tangential discharge pocket drawn to a much larger scale. Fig. 4 shows the cap, 100 which is located in the mouth of the pocket, in front elevation.

The projectile illustrated is designated by the reference numeral 10 and has its front end tapered to a point in the usual manner, 105 as shown at 11. The rear end of the projectile is formed into a tapered section 12 and has a curved or rounded end 13 of relatively small radius. The larger end of the tapered section 12 joins the cylindrical cen- 110

tral section of the projectile by curves as indicated at 14. Near the larger end of the tapered section where the cross-section 2-2 is taken, the projectile is provided with a plurality of pockets 15-15 and 16-16 which are arranged in pairs, the pockets of each pair being at equal distances on opposite sides of the center and having their discharge ends at diametrically opposite points in the circumference of the circular section formed by the intersection of a transverse plane and the projectile.

The pockets are not necessarily arranged in pairs as any number may be employed. I prefer, however, that the forces exerted shall be substantially balanced relative to the axis of the projectile. Each of the pockets is closed at its inner end and is loaded with a suitable charge of quick-burning powder or other explosive. The charge with which the gun is loaded in the usual manner, comprises a relatively slow-burning explosive material, the result being that the tangential charges are fired and the reaction of the tangential charges which takes place while the projectile is in the gun, produces a high-speed rotation of the projectile. Furthermore, the explosive gases formed by the discharge of the tangential charges are added to, and act in conjunction with, the explosive gases resulting from the main discharge.

As above indicated, the direction of the projectile is absolutely maintained by bore of the gun, and since the tangential discharge charges are not active, after the projectile leaves the muzzle of the gun, they have no tendency to interfere in any way with the accuracy of the shot.

Attention is particularly directed to the fact that the tangential discharge pockets are located in a transverse plane, which is near the rear of the projectile, and in the tapering section thereof, thereby producing a suitable space in which the explosive gases may be discharged.

While I prefer to have the rear of the projectile tapered since the best results are obtained in this way, my invention is not limited in this regard and the rear of the projectile may be reduced in size to provide the annular space 23 into which the tangential pockets are discharged. The pockets are preferably loaded with loose quick-burning powder to insure a very rapid action.

The tangential pockets may be closed in any suitable manner after the explosives are in place,—for example, the projectile at the mouth of each pocket may be provided with grooves 19 to receive a cap 20. This may comprise a pair of washers or perforated disks 21 of thick paper or cardboard between which is held a thin sheet 22 of oil or paraffin paper. The cap may be formed in some other suitable manner so long as it is adapted to be instantly destroyed when

the main charge is fired in the gun, thereby insuring that the quick-firing charges in the pocket are exploded.

The body of the projectile at the mouth of the pockets is cut away, curved, or shaped as indicated at 24, to provide ready discharge paths for the gases from the pockets into the annular space 23.

Strictly, the pockets cannot be tangentially disposed or discharge tangentially relative to the surface of the projectile but a large component of the discharge force from each pocket is tangential and since this is the only component which is useful for producing rotation the pockets are described as "tangential".

The projectile of my invention is particularly advantageous because not only is its rear end so tapered as to reduce the friction and windage losses to a minimum, but also the same tapering provides the annular space into which the explosive in the tangential pockets discharge. The reduction in friction and the elimination of the partial vacuum at the rear increases the flight of the projectile by a large percentage and this is further increased by the fact that the retardation due to the gun reflexing, is avoided. A projectile of superior efficiency and effectiveness is therefore produced.

What I claim is:

1. A projectile having a cylindrical body and a tapered rear end, a plurality of tangential discharge pockets having openings in the tapered rear end, quick-firing explosives therein, and caps for holding the explosives in position, said explosives being adapted to be fired by the explosion of the gun charge, whereby a rotation of the projectile is produced while the projectile is in the gun.

2. A projectile having a reduced section to provide an annular space at the rear, a plurality of tangential discharge pockets opening into said space, and quick-burning powder in said pockets.

3. A projectile having a reduced section to provide an annular space at the rear, a plurality of tangential discharge pockets opening into said space, quick-burning powder in said pockets, and means, adapted to be disrupted by the gun charge, for holding the quick-firing powder in the pockets.

4. A projectile having a reduced section to provide an annular space at the rear, a plurality of tangential discharge pockets opening into said space, quick-burning powder in said pockets, and a cap for each pocket comprising relatively stiff perforated sheets and a thin film between them.

5. A projectile having a reduced section to provide an annular space at the rear, a plurality of tangential discharge pockets opening into said space, quick-burning powder in said pockets, and a cap for each

pocket comprising relatively stiff washers and a thin sheet of fabric stretched between the washers.

6. A projectile having a reduced section to 5 provide an annular space at the rear, a plurality of tangential discharge pockets opening into said space, quick-burning powder

in said pockets, and a cap for each pocket comprising perforated cardboard sheets and a thin sheet of paraffin paper sealed between them.

In witness whereof, I have hereunto set my hand this 7 day of October, 1915.

ANDREW M. COYLE.
